UNITED STATES PATENT OFFICE.

PAUL E. BRENEMAN, OF DETROIT, MICHIGAN, ASSIGNOR TO THE STUDEBAKER CORPORATION, OF SOUTH BEND, INDIANA, A CORPORATION OF NEW JERSEY.

BODY CONSTRUCTION.

Application filed March 4, 1926. Serial No. 92,223.

This invention relates to automobile body pillars, and the principal object is to provide such a pillar made principally from pressed metal in such a manner that it will be light but strong and economical to manufacture.

Another object is to provide a sheet metal body pillar comprising an inner and an outer member secured together to form a hollow structure.

Another object is to provide a body pillar comprising two channel-shaped metal stampings adapted to extend from the sill to the roof rail, one stamping fitting within and being secured to the other to form a hollow structure within which suitable supports are provided for various door engaging devices.

Another object is to provide a pillar of the type described comprising an outer channel-shaped member closed by a second channel-shaped member, the outer member being cut away at suitable points to receive door dovetails and door bumpers, the supports for the dovetails and bumpers being secured to the inner face of the outer member in matching relation to said cut-away portions, and the inner member forming an abutment for certain of said parts.

Another object is to provide a pillar of the type described comprising an outer channel-shaped member closed by a second channel-shaped member facing in the same direction, to form a hollow structure, the channel of the second member being filled with a strip of wood providing a tacking strip for interior upholstery material and other purposes.

Another object is to provide a pillar as above described to the upper end of which is secured vertical and horizontal attaching flanges which are adapted to receive both the bottom and a side face of the roof rail thereby to be rigidly secured to the same.

A further object is to provide an inwardly extending horizontal flange adjacent the lower end of the pillar for connection to the top face of the body sill, the edges of the inner channel member below the flange being suitably bent to provide vertically extending attaching flanges adapted to be secured to the outer edge of the sill.

The above being among the objects of the present invention, the same consists of certain features of construction and combinations of parts to be hereinafter described

with reference to the accompanying drawings, and then claimed, having the above and other objects in view.

In the accompanying drawings which illustrate a suitable embodiment of the present invention, and in which like numerals refer to like parts throughout the several different views:

Figure 1 is a perspective view of an automobile body in which the present invention is incorporated.

Figure 2 (Sheet 2) is a perspective view, from the inner face side, of the completed pillar embodying the present invention, showing a portion of a wooden roof rail secured thereto.

Figure 2^a (Sheet 1) is a perspective view of the lower portion of the pillar of Figure 2, showing the same secured to a wooden body sill.

Figure 2^b (Sheet 1) is a transverse sectional view through the sill shown in Figure 2^a taken on the near side of the pillar, more clearly showing the manner in which the pillar is secured thereto.

Figure 2^c (Sheet 2) is a section taken on the line 2^c—2^c of Figure 2.

Figure 3 is a perspective three-quarter front face view of the outer channel pillar member only.

Figure 3^a is a perspective three-quarter rear face view of the channel member shown in Figure 3.

Figure 4 is a perspective three-quarter front face view of the inner channel pillar member only.

Figure 4^a is a perspective three-quarter rear face view of the inner channel member shown in Figure 4.

Figure 5 is a perspective view of the foot flange which is adapted to be secured to the inner channel member adjacent its lower edge.

Figure 6 is a perspective view of the horizontal flange member which is adapted to be secured to the upper end of the pillar.

Figure 7 is a perspective view of the vertical flange member which is adapted to be secured to the upper end of the pillar.

Figure 8 is a perspective view of the wooden block which is adapted to be secured between the two channel members at the point where the door striker plate is secured.

Figure 9 is a perspective view from the front face of the inner channel member to

which the parts shown in Figures 5, 6, 7 and 8 are secured in assembled relation thereto.

Figure 9^a is a perspective view from the rear face of the inner channel member as shown in Figure 9.

Figure 9^b is an enlarged fragmentary perspective view of the upper portion of the inner channel member shown in Figure 9^a, the attaching flanges for the roof rail being more clearly shown.

Figure 10 (Sheet 5) is a perspective view from the front face of the inner channel member with various attached parts as shown in Figure 9, assembled to the outer channel member, various other parts being also shown in assembled relation thereto.

Figure 10^a is a perspective view of the parts as shown in Figure 10, taken from the rear face thereof.

Figure 11 is an enlarged perspective fragmentary view of the pillar showing the door dove-tail in assembled relation thereto.

Figure 11^a is a perspective view of the spring wear plate of the door dove-tail.

Figure 11^b is a perspective view of one of the rubber blocks employed in the door dove-tail.

Figure 11^c is a perspective view of the various members of the door dove-tail in the relationship which they assume towards each other when assembled in the pillar.

Figure 11^d is a fragmentary perspective view of the pillar, showing in dotted lines the position which the assembly shown in Figure 11^c assumes in relation thereto.

Figure 12 (Sheet 4) is a perspective view of the door bumper and support in the position which they assume in relation to each other when assembled to the pillar.

Figure 12^a (Sheet 4) is a fragmentary perspective view of the pillar showing the members of Figure 12 secured thereto in assembled relation therewith.

Figure 13 (Sheet 4) is a perspective view of the latch striker plate which is secured to the pillar in the position shown in Figures 2, 10 and 10^a.

In Figure 1 an embodiment of the present invention is shown in the pillar which, for this particular view, is designated by the numeral 20, and which extends between the sill 21 and top rail 22 of the automobile body 23 between the front door 24 and rear door 25 thereof. In the embodiment shown neither of the doors 24 or 25 is shown hinged on and supported by the pillar 20, and the drawings and following description refer to the pillar as shown in Figure 1, although it will be readily apparent that by slight changes the doors may be hinged to the pillar 20, and such is within the scope of the present invention.

The pillar, indicated by the numeral 20 in Figure 1, and shown in enlarged view in

completed condition in Figure 2, has for its main body portion two pressed metal members 26 and 27 which, when suitable auxiliary parts are attached thereto, go to make up the completed pillar. The member 26, which I prefer to call the outer member, is shown alone in perspective in Figures 3 and 3^a, and its section is shown in Figures 2^c, 11^d and 12^e which latter views show this member in combination with other parts. 75

As shown, it comprises a pressed sheet metal member extending from the body sill 21 to the roof rail 22, its front face portion, which for convenience is also designated by the numeral 26, being suitably curved in its length 80 to conform to the curve of the side of the body 23 at the point where it is positioned, and its inner edges being substantially straight from its upper end to a point near the bottom end thereof. In section it is 85 channel-shaped with the corners rabbeted to match the corresponding rabbeted edges of the doors, the metal being bent back and then out from the front face 26 to form the faces 28 and 29 of the rabbet, and then rearwardly to form the main side faces 30. Because of the curved outer face of the pillar and the slight curve only of the inner face, the side faces 30 become relatively narrow at their lower ends, this being done for construction purposes. If desired, the lower end of the face portion 26 may be extended and bent inwardly to provide an attaching flange as illustrated in Figures 2, 2^b, 3^a and 10^a for securing to the bottom face of the body sill 21 as shown in Figure 2^b. Openings 31 are provided in the faces 29 and 30 at their point of junction for reception of the door bumpers as will be described later, and other openings 32 are provided in the same faces for the door dove-tail which will also be described later. In the construction shown, depressions or pockets 33 are provided in the faces 30 in which are secured door latch strike plates 34, the pocket being necessary for use in certain forms of door and latch constructions not shown, but may be dispensed with for use in connection with the conventional types of door and latch constructions. 110

The inner channel member 27 has a face portion which, for convenience is also designated as 27, and sides 35, it being formed to such shape and dimensions that it fits into and nests within the free edges of the outer member 26, it being positioned in the same relative direction as the outer member 26 with its free edges flush with the free edges of the outer member 26, in which position it is adapted to be secured by spot welding, riveting or the like. It is provided with depressions 36 and 37 which serve as socketing seats for the upper end and lower door bumpers blocks 38 which will be described later. Depressions 39 are also provided for 115 120 125 130

the same reason for the door dove-tail blocks 40 which will also be described later. Notches 41 are formed in its edges as shown in Figures 4, 4^a, 9 and 9^a to provide a recess 5 for the edge of the pocket 33 in the outer member 26 to seat in. If desired, key hole slots such as 42 may be provided for removably securing the wooden filler and tacking strips therein as will be described later.

10 It will be noticed that, due to the narrowness of the lower end of the pillar and in order to retain the strength at this point, the lower end of the inner member 27 is formed to the same section as the lower end 15 of the outer member 26, that is to say, it is provided with rabbeted edges so as to be capable of nesting within the rabbeted front face of the outer member, and further, that the sides 35 at the extreme lower end are 20 bent back on themselves to provide vertical attaching flanges 43 which are adapted to be secured to the outer edge of the body sill 21. An L-shaped trough-sectioned stamping 44, shown in perspective in Figure 5, is secured to the lower end of the inner member 25 27, as shown in Figures 9 and 9^a; with its vertical leg nested within and welded or otherwise secured thereto, the horizontal leg extending inwardly away from the face of 30 the pillar in a plane flush with the top of the attaching flanges 43 to provide an attaching flange for securing to the top face of the body sill 21.

The upper end of the inner member 27 is 35 provided with means for receiving the roof rail 22 as follows: An L-shaped stamping (see Figure 6) having a vertical leg portion 45 and outspread horizontal flanges 46 is secured to the upper end of the inner member 27, as shown in Figures 9 and 9^a, by riveting or welding the leg 45 to the outside face portion 27. The horizontal flanges 46 are flush with the upper end of the member 27 and are turned outwardly in a position 45 to be secured to the roof rail 22. A second stamping (see Figure 7) having a vertical leg 47 and an offset vertical flange 48 is secured within the upper end of the member 27. (see Figures 9^a and 9^b) by riveting or 50 welding the leg 47 thereto, the flange 48 being offset from the outer face of the pillar so that it is flush with the free edges of the member. These two stampings thus form a horizontal flange on which the roof rail 22 55 may rest, and a vertical flange against which the inner face of the roof rail 22 may abut and be secured as shown in Figure 2.

In addition, a wooden block 49, formed to fit within the outer member 26, is secured to 60 the face of the member 27 at a point corresponding to the position which the striker plate 34 is positioned on the outer member 26, thereby to provide means for securing the striker plate in position when the parts 65 are completely assembled, and to relieve local

stresses at that point due to the door latch bolt striking the striker plate when the door is slammed shut.

The inner member 27 as thus described, with the stampings secured to the upper and lower ends and the block 49 secured in place, is ready to be assembled to the outer member 70 26, but before this is done, the door bumper and dove-tail supports are secured to the inner face of the member 26. 75

The supports for the door-bumpers (shown best in Figure 12), each comprise a piece of strip metal bent to form a dove tail recess having a base portion 50 and convergent side portions 51 terminating in outwardly 80 extending attaching flanges 52 parallel to the base 50. These supports are secured to the inside face of the side portions 30 of the main outer member 26 with the recess opening outwardly and in matching relation with its corresponding opening 31 in the main outer member 26, the flanges 52 being riveted or welded to the inside face of the side portion 30. The door bumper blocks 38 are provided with tapered side walls complementary to the convergent side walls 51 of their supporting members and are adapted to be received therein as indicated in Figure 12, a screw or the like such as 53 being preferably provided for passing through each 85 block 38 and into the support for preventing relative displacement of the blocks 38 in respect thereto. It will be noted that the blocks 38 are longer than their supports so that when assembled thereto, which is preferably not done until the outer main member 26 has been assembled to the inner member 27, they project a substantial amount past the rabbet faces 28 so as to be in proper position to engage the complementary faces 90 of the door 24 or 25 which engage the same.

The supports for the door dove-tails (best shown in Figure 11^c) are likewise formed of sheet metal to provide a recess, having a bottom wall 54 and parallel side walls 55 terminating in outwardly bent attaching flanges 56. These supports are secured to the inside face of the member 26 in matching relation to the openings 32 in the same manner as the supports for the door bumpers previously described. Their position, when assembled, is best shown by dotted lines in Figure 11^d. The dove-tails themselves each comprise two rubber blocks 40 seated in the recess formed by the bottom wall 54 and side walls 55 of their support and separated by and held against the side walls 55 by means of a U-shaped spring metal member 57 shown alone in perspective in Figure 11^a and shown best in operative position in respect to the blocks 40 in Figure 11^c. The spring 57 is positioned with the open end of the U facing towards the outside face 26 of the pillar, which open end is in matching relation with that part of the opening 32 formed 105 110 115 120 125 130

in the rabbet face 29 so as to be capable of receiving the usual male portion of the dove-tail (not shown) secured to the edge of the door in matching relation therewith. The blocks 40 and spring 57 may be assembled in position after the outer member 26 and inner member 27 have been assembled together, the spring 57 holding the parts in operative position.

10 The outer member 26 with the door bumper and door dove-tail supports secured thereto is in condition to receive the inner member 27 with its auxiliary parts as shown in Figures 9 and 9^a, the inner member 27 nesting within the outer member 26 as previously described and as illustrated in Figures 10, 10^a, 11^a, and 12^a, the side walls 35 of the inner member 27 being welded or otherwise secured to side walls 30 of the outer member thus providing a hollow structure of great strength and of comparatively light weight. After these two members 26 and 27 are thus assembled together, the door bumper blocks 38 and door dove-tail blocks 40 and spring 57 are assembled, although they may be assembled beforehand but may introduce difficulties in the finishing of the pillar if so done. When the blocks 38 are inserted and secured in place their inner ends are received by the depressions 36 in the inner member 27 and abut against the bottom thereof so that the inner member 27 takes all of the heavy strains imposed on the door bumpers. The rubber blocks 40 and the rear end of the spring 57 likewise are received in and abut against the bottom of the depressions 39 of the inner member 27 for the same reasons as referred to above in connection with the door bumpers.

45 The wooden block 49 is closely received between the bottoms of the pockets 33 as previously described, and the door latch strike plates 34 are secured in the pockets 33 by passing screws through the bottom of the pockets and into the block 49.

50 The pillar as thus far described is in the state of completion illustrated in Figures 10 and 10^a. The next step is to insert the wooden pillar or tacking strips in the back face thereof as illustrated in Figures 2 and 2^a. As shown in those figures an upper tacking strip 58 and a lower tacking strip 59 are provided, the upper one being permanently secured in place by any suitable means such as by screws or the like passing through the side faces 30 and 35, and the lower one may be removably secured in place by headed pins (not shown) on its concealed face co-operating with the key-hole slots 42 previously described, or both may be either removably or permanently secured in place as best suits conditions.

55 The pillar is now ready to be finished and

assembled to the automobile body of which 65 it is to form a part, the upper end being secured to the roof rail 22 in the manner shown in Figure 2 and as previously described, and the lower end being secured to the body sill 21 as shown in Figures 2^a 70 and 2^b.

75 While a wooden roof rail and body sill has been shown in the accompanying drawings, with the pillar ends formed accordingly to receive them, it will be evident that slight changes may be made in the ends to adapt them for securement to metallic rails and sills of various designs, and these and other formal changes may be made in the 80 specific embodiment of the invention described without departing from the spirit and substance of the broad invention, the scope of which is commensurate with the appended claims.

85 What I claim is:—

1. A pillar for an automobile body comprising an inner and an outer sheet metal trough sectioned member secured together in nested relation to form a hollow structure, an angle member secured to the inner face of said inner member at the upper end thereof to provide a horizontal attaching flange, and an offset member secured to said member adjacent to said angle member to provide a vertical attaching flange.

90 2. A pillar for an automobile body comprising an inner and an outer sheet metal trough sectioned member secured together in nested relation to form a hollow structure, means secured to the upper end of said inner member providing horizontal and vertical attaching flanges, an angle member secured within the trough of said inner member adjacent the lower end thereof to form a horizontal attaching flange, and the sides of said inner member below said angle member being bent inwardly to provide a vertical attaching flange.

95 3. A pillar for an automobile body comprising an inner and an outer sheet metal 100 trough sectioned member secured together in nested relation to form a hollow structure for the greater part of its length, said outer member being formed to present rabbeted outer corners and the side walls thereof 105 gradually reduced in depth towards the lower end thereof, said inner member being formed with complementary matching surfaces at its lower end engaging the inner 115 surface of said outer member, an attaching flange member secured to said inner member adjacent the lower end thereof, and the side walls of said inner member below said flange member being bent back on themselves to 120 provide other attaching flanges.

125 Signed by me at Detroit, Michigan, U. S. A., this 27th day of February 1926.

PAUL E. BRENEMAN.
